LEVER HANDLE UNIT

Leo J. Maffei, New Britain, Conn., assignor to The American Hardware Corporation, New Britain, Conn., a corporation of Connecticut

Filed July 14, 1959, Ser. No. 56,783

Term of patent 14 years

(Cl. D10—8)

Fig. 1.

Fig. 2.

Fig. 3.

Fig. 4.

Fig. 5.

Fig. 6.

Fig. 7.

Fig. 8.

Fig. 1 is a front elevational view of a lever handle unit, showing my new design.

Fig. 2 is an elevational side view thereof.

Fig. 3 is a perspective view thereof on a smaller scale.

Fig. 4 is an elevational end view thereof taken from the bottom of Fig. 1.

Fig. 5 is a sectional view on line 5-5 of Fig. 1.

Fig. 6 is a sectional view on line 6-6 of Fig. 1.

Fig. 7 is a sectional view of the handle only on line 7-7 of Fig. 1.

Fig. 8 is a side view, partly in central vertical section, of the handle only.

I claim:

The ornamental design for a lever handle unit, substantially as shown.
